UNITED STATES PATENT OFFICE.

HEINRICH BOLTSHAUSER, OF ZURICH, SWITZERLAND.

RAILWAY TRAIN.

Application filed November 8, 1921. Serial No. 513,697.

To all whom it may concern:

Be it known that I, HEINRICH BOLTSHAUSER, a citizen of the Republic of Switzerland, residing at Zurich, Switzerland, have 5 invented certain new and useful Improvements in Railway Trains, of which the following is a specification, reference being had therein to the accompanying drawing.

The present invention relates to improvements in railway trains and has for its object to provide a heating installation for railway trains driven by a steam locomotive working with condensation and provided with a re-cooling device for the cooling 10 water of the condenser. According to the invention, heaters fitted to the railway cars constitute parts of the re-cooling device in which heaters the waste heat of a portion of the cooling water for the condenser is 15 utilized for heating purposes.

In steam locomotives working with condensation the cooling water required in the condenser is preferably recooled by an air current induced upon the running of the 20 locomotive in a recooling device coupled to the latter. When designing such re-cooling devices certain dimensions cannot be exceeded on account of the prescribed railway clearance gauge and in order to comply with 25 certain conditions arising from the practical working of the device. In consequence thereof the re-cooling devices used do not work with the desired efficiency, so that the 30 vacuum in the condenser is not particularly high. In arranging the heaters of the cars to form parts of the re-cooling device it is possible to re-cool the cooling water for the condenser to a lower temperature than is the case if the re-cooling of the cooling 35 40 water takes place only in a re-cooling device proper, whereby a better vacuum in the condenser can be obtained.

Furthermore a secondary advantage is attained in that the waste heat contained in the cooling water which otherwise would be lost is utilized in a known manner. The present invention proves advantageous when the train travels up long slopes or inclines and the locomotive can, as a rule, not supply 45 any steam for heating purposes and the re-cooling of the cooling water is not efficient on account of the air current not being so strong, owing to the reduced speed of the train, as would be necessary in view of the 50 increased output of the locomotive.

Several constructional examples of the in-

vention are diagrammatically illustrated in the accompanying drawing, in which:

Fig. 1 is a side view, partly in section, 60 of a first constructional example,

Fig. 2 shows part of an installation in which the portion of the cooling water that has been cooled in the heaters of the railway train is then led into the re-cooling device proper and

Fig. 3 illustrates part of an installation in which the portion of the cooling water used for heating purposes is raised to a higher temperature previous to its admission into the heaters of the cars.

Referring to the drawing, 1 denotes the steam turbine which actuates the driving axles 3 of the locomotive through the interposition of a transmission gear 2. The exhaust steam from the steam turbine 1 enters the surface-condenser 4 to which cooling water is supplied through a conduit 5. The cooling water heated in the surface condenser 4 is caused, by the pump 6, to flow through the conduit 7 to a cooling vehicle 8 in which it is, in a known manner, re-cooled by the action of an air-current induced upon the running of the locomotive and then collected in a tank 9, from where it is returned to the condenser 4 by means of the pump 10 and the conduit 5. From the conduit 7 a conduit 11 branches off and extends over the length of the train, a valve 12 being inserted in the conduit 11. The valve 12 can be operated from the cab of the locomotive by means of the arrangement 16. To the conduit 11 there are connected the heaters 13 by which the cars 17, coupled to the locomotive, are heated by a warm water heating system. The heaters 13 are in turn connected to a conduit 14 extending along the train, the conduit 14 being connected to the conduit 5. At the point of connection between the conduits 14 and 5 a valve 15 is provided which can also be actuated from the driver's cab by means of the arrangement 18.

The operation of the above described installation is as follows: If the cars 17 are to be heated the valves 12 and 15 are adjusted 105 to provide for an open connection between the conduits 7 and 11 and the conduits 5 and 14 respectively. A portion of the cooling water discharged from the condenser 4 by means of the pump 6 flows into the several heaters 13 of the cars, in which it is re-cooled by the occurring emission of heat 110

whereupon it is caused to flow back to the condenser 4 together with the water drawn from the tank 9 by the action of the pump 10. In this way a portion of the comparatively warm water leaving the condenser 4 flows as heating medium through the heaters or radiators 13 of the warm-water heating installation of the train which forms part of the re-cooling device proper, in order 10 to be re-cooled in said heaters.

If the cars are not to be heated the connections between the conduits 7 and 11 and 5 and 14 respectively are interrupted.

If it is deemed necessary the portion of 15 the comparatively warm cooling water leaving the condenser 4 and utilized for heating purposes, after having been re-cooled in the heaters 13 of the warm-water heating installation of the railway train, may be led 20 from the conduit 14 through the conduit 19 into the re-cooling device 8, which arrangement is illustrated in Fig. 2.

As is shown in Fig. 3 the portion of the comparatively warm cooling water proceeding 25 from the condenser 4 may, if necessary, pass an additional heating apparatus 20 previous to its flow through the heaters 13 of the cars, for the purpose of raising its temperature.

30 The additional heating apparatus is supplied with live steam from the locomotive through a conduit 21. The water of condensation formed in the heating apparatus 20 flows through a conduit 22 into the water 35 tank 23 of the cooling vehicle 8.

I claim:

1. In a railway train, the combination, of 40 a steam-locomotive provided with a condenser, a re-cooling device for the cooling water used for condensing purposes, cars, heaters provided in said cars and adapted to

form parts of said re-cooling device, and means for diverting a portion of the cooling water to said heaters for utilizing the waste heat contained in said portion of the water to 45 heat the cars whereby a better re-cooling effect and thereby a higher vacuum in the condenser is attained.

2. In a railway train, the combination, of a steam-locomotive provided with a condenser, a re-cooling device for the cooling water used for condensing purposes, cars, heaters provided in said cars and adapted to form parts of said re-cooling device, conduits for diverting a portion of the cooling 55 water to said heaters for utilizing the waste heat contained in said portion of the cooling water to heat the cars and to improve thus the re-cooling effect and the vacuum in the condenser, and valves to control the portion 60 of the cooling water diverted to said heaters.

3. In a railway train, the combination, of a steam-locomotive provided with a condenser, a re-cooling device for cooling the water used for condensing purposes, cars, 65 heaters provided in said cars and adapted to form parts of said re-cooling device, means for diverting a portion of the cooling water as heating medium to said heaters to heat the cars and to improve the re-cooling effect and 70 the vacuum in the condenser by cooling said portion of the cooling water in the heaters, a heating arrangement connected to said means for supplying said portion of the cooling water to the cars, and means to supply live 75 steam from the locomotive to said heating arrangement for raising the temperature of the heating medium previous to its being supplied to said heaters.

In testimony whereof I affix my signature. 80

HEINRICH BOLTSHAUSER.
